(57) **CLAIM**

The ornamental design for a set of magnetic tiles as shown and described.

DESCRIPTION

FIG. 1 is a front, right and top perspective view of a set of magnetic tiles showing my design.

FIG. 2 is a front, left and top perspective view of the triangular block of the set of magnetic tiles of FIG. 1 shown separately for ease and clarity of illustration.

FIG. 3 is a rear, right and bottom perspective view of the triangular block of the set of magnetic tiles in FIG. 2.

FIG. 4 is a front elevation view of the triangular block of FIG. 2.

FIG. 5 is a rear elevation view of the triangular block of FIG. 2.

FIG. 6 is a left side elevation view of the triangular block of FIG. 2.

FIG. 7 is a right side elevation view of the triangular block of FIG. 2.

FIG. 8 is a top plan view of the triangular block of FIG. 2.

FIG. 9 is a bottom plan view of the triangular block of FIG. 2.

FIG. 10 is a front, left and top perspective view of the square block of the set of magnetic tiles of FIG. 1 shown separately for ease and clarity of illustration.

FIG. 11 is a rear, right and bottom perspective view of the square block of the set of magnetic tiles in FIG. 10.

FIG. 12 is a front elevation view of the square block of FIG. 10.

FIG. 13 is a rear elevation view of the square block of FIG. 10.

FIG. 14 is a left side elevation view of the square block of FIG. 10.

FIG. 15 is a right side elevation view of the square block of FIG. 10.

FIG. 16 is a top plan view of the square block of FIG. 10; and,

FIG. 17 is a bottom plan view of the square block of FIG. 10.

The broken lines depict portions of the set of magnetic tiles that form no part of the claimed design.

1 Claim, 17 Drawing Sheets
